UNITED STATES PATENT OFFICE.

ERNEST M. COLE AND HIRAM ALLEN, OF WILLIAMSBURG, KANSAS.

PUMP ATTACHMENT.

Application filed August 24, 1923. Serial No. 659,166.

This invention relates to an attachment especially designed for use in wells, cisterns or the like for purifying and aerating the water contained therein.

5 The primary object of the invention is to provide a tank to be located in the well or cistern, submerged in the water contained therein, whereby water in the cistern is aerated, the air entering the tank at the 10 bottom and passing upwardly to the surface of the water in the cistern or well, while the tank refills with water.

Another object of the invention is to provide automatic means for admitting water 15 to the tank, should the water in the tank be used therefrom more rapidly than the water could pass into the tank through the usual filling opening thereof.

With the foregoing and other objects in 20 view which will appear as the description proceeds, the invention resides in the combination and arrangement of parts and in the details of construction hereinafter described and claimed, it being understood 25 that changes in the precise embodiment of the invention herein disclosed, may be made within the scope of what is claimed without departing from the spirit of the invention.

Referring to the drawings:

30 Figure 1 is a sectional view through the tank forming the subject matter of the invention.

Figure 2 is a transverse sectional view therethrough.

35 Figure 3 is a sectional view taken on line 3—3 of Figure 1.

Referring to the drawing in detail, the tank is indicated generally by the reference character 5, the same being of any desired 40 construction to meet the requirements of use.

The upper wall of the tank is formed with a filling opening 6 to allow water to enter the tank as the water is used therefrom, it 45 being understood that the tank is to be positioned in the cistern or well, submerged.

The upper wall of the tank is formed with an opening 7 which is normally closed by the cap 8, the opening 7 being relatively 50 large so that access may be had to the interior of the tank to repair or replace the valve members thereof. The discharge pipe from the tank is indicated at 9 and has its lower end connected with the tank at 10 providing communication between the pipe 55 9 and tank 5 so that when the pump struc-

ture located at the upper end of the pipe 9 and which is omitted in the present showing, is operated, water will be drawn from the tank 5 and into the pipe 9 where the same 60 will be discharged at the upper end of the pipe 9.

Communicating with the tank 5 at the opposite end thereof, is an air inlet pipe 11 that has an inwardly extended end 12 supplied with a one-way valve member 12' which valve member allows air under pressure to enter the tank 5 through the pipe 11. The upper end of the pipe 11 extends above the cistern and has connection with a suitable source of air supply to be forced into the tank, the air escaping from the tank at 6 and passing upwardly aerating and cleaning the water in the cistern or 70 well on its upward passage.

Since the tank 5 is submerged it will be obvious that air passing from the tank must pass through the water in the cistern or well in which the tank 5 is positioned, aerating the water within the cistern or well. 80

Formed in the bottom of the tank 5, is an opening 13 which is normally closed by means of the ball valve 14 supported at the lower end of the valve rod 15 which has connection with the float 16 so that when the water in the tank 5 rises above the float 16, the valve 14 will be closed to prevent water from entering the tank 5 through the opening 13. 85

Operated by the movement of the rod 15 90 is a ball valve 17 that is disposed within the tank 5 and operates to close the opening 18, when the water in the tank 5 has reached a predetermined level and prevent water from entering the tank through the opening 18. This ball valve 17 is carried at the free end of the rod 19 which is pivotally supported by the arms 20, the opposite end of the rod 19 having pivotal connection with the rod 15 at 21. 95

From the foregoing it will be obvious that should the water be withdrawn from the tank 5 more rapidly than water could enter through the filling opening 6, the float 16 would move downwardly, when the water in tank 5 reaches a predetermined level, thereby unseating the valves 14 and 17 and allowing water to enter the openings 13 and 18. 105

In the use of the device, air is forced 110 through the pipe 11 and enters the tank 5, aerating and cleaning the same prior to

its passage through the supply pipe 9 of the pump, also aerating and cleaning water in cistern or well prior to its entrance into tank 5.

5. What is claimed as new is:—

In a device of the character described, a tank adapted to be submerged in a body of water, said tank having an inlet opening in the upper portion thereof, said tank having an inlet opening in the bottom thereof, a float controlled valve for controlling the passage of liquid into the tank through the opening in the bottom thereof, a pipe ex-

tending into the bottom of the tank, a one way valve member positioned on one end of the pipe to prevent the passage of liquid into the pipe, a substantially large outlet pipe communicating with the tank at the base thereof, and said first mentioned pipe adapted to supply air under pressure to the tank.

In testimony that we claim the foregoing as our own, we have hereto affixed our signatures.

ERNEST M. COLE.
HIRAM ALLEN.
